UNITED STATES PATENT OFFICE.

WILSON PINES, OF ROGERS, MICHIGAN.

GRADER.

1,287,424.

Specification of Letters Patent. Patented Dec. 10, 1918.

Application filed January 30, 1917. Serial No. 145,469.

To all whom it may concern:

Be it known that I, WILSON PINES, a citizen of the United States, residing at Rogers, in the county of Presque Isle and State of Michigan, have invented new and useful Improvements in Graders, of which the following is a specification.

This invention comprehends improvements in graders or screens for stone, ore, coal and like material and has for its primary object the provision of such a machine having a novelly constructed grading or screening table over which the material is fed and through which the under sized particles thereof fall.

Another and more specific object of the invention is to provide a grader or screen having a screening table which includes a plurality of transverse parallel shafts upon each of which is fixed a plurality of eccentrically mounted fingers, the fingers of each shaft being disposed at different angles relative to the plane of the table so that they will not simultaneously engage the material passing thereover.

The invention also aims to generally improve machines of this nature to render them more practical, desirable and efficient.

With these and other objects in view as will become more apparent as the description proceeds, the invention consists in certain novel features of construction, combination and arrangement of parts as will be hereinafter fully described illustrated and claimed.

In the drawings,

Figure 1 is a top plan view of the grader. Fig. 2 is a side elevation of the grader.

Fig. 3 is an end elevation of the machine.

Fig. 4 is a longitudinal sectional view showing the position of the fingers on the transverse shafts.

Fig. 5 is a fragmentary side elevation showing a modified form of gearing, and

Fig. 6 is a perspective view of one of the shafts and fingers thereon.

Referring in detail to the drawings by numerals, 1 and 2 designate the frame legs at the receiving or intake end of the grader and 3 and 4 indicate the frame legs at the discharge of the machine. The legs in each pair are connected by cross pieces 5 and 6 and by the inclined brace bars 7. The legs are connected at their upper ends, to the parallel side bars 8 and 9 which form a part of the grading or screening table 9'.

Extending transversely across the machine are a plurality of shafts 10, 11, 12 and 13 which are rotatably mounted in bearings 14 supported on the bars 8 and 9. Rigidly secured to each of the shafts is a plurality of eccentrically mounted fingers 15 which are arranged at different angles relative to a horizontal plane. Each of these fingers is elongated having a convex forward edge 16 and a concave rear edge 17. The fingers taper from their butt portions 18 toward their pointed terminals 19 as clearly shown in Fig. 6. Extending between the longitudinal rows of the eccentric fingers are the partition or division bars 20 which are formed with openings for the passage of the transverse shafts and which are connected adjacent their ends to the cross bars 6 by uprights or arms 21.

Connected to each of the bars 8 and 9 is a wall 22 which projects upwardly above the plane of the screening table and which forms part of the body of the grader. These walls are inclined downwardly and inwardly adjacent their lower edges as indicated at 23 to direct material to be graded on to the grading table. At the receiving end of the machine between the side walls 22 is mounted a chute 24 having the bottom wall 25 and side walls 26. This chute is pivotally connected near its forward edge to the side walls 22 by means of the fasteners 27 and inclined rearwardly and downwardly into engagement with the inturned portions of the side walls 22. Since the chute is pivotally mounted it may be swung upwardly in an out of the way position to leave the table entirely uncovered for cleaning purposes.

For rotating the transverse shafts 10, 11, 12 and 13, I provide upon each of them a fixed sprocket 28 over which passes an endless sprocket chain 29. The forward shaft 10 is equipped with a pulley 30 over which may be passed a drive belt to furnish power to the grader.

The transverse shafts may be driven in other ways from that just described and for instance instead of using the sprockets and chain, I may provide upon each of the shafts 10 a spur gear 31 which meshes with an idler 32. In both forms of transmission mechanism, it will be apparent that the transverse shafts are all driven in the same direction so as to cause the eccentrically mounted fingers to advance material along the grading table. If desired, the rear legs of the

grader may be made longer than the forward legs so as to dispose the screening table at an angle to the horizontal plane with its discharge end elevated above its receiving end 5 as shown in the drawings.

In operation, the material to be graded or screened is dumped on to the inclined chute 24 and moves downwardly on to the screening table where it is acted on by the 10 revolving eccentrically mounted fingers 15. As the transverse shafts are all driven in the same direction, the fingers will both agitate the material and advance such pieces thereof as do not fall through the openings. 15 By arranging the fingers of each shaft at different angles relative to the plane of the table they will not simultaneously engage the material thereof and therefore less power is required to operate the machine 20 than would be the case were the fingers disposed at the same angle to the plane of the table. This is an important feature of the invention since besides requiring less power to operate the machine, it makes it possible 25 to construct the various parts of the device of a lighter material than would be the case were all of the fingers to simultaneously act upon the material. The eccentric fingers being thus mounted cause the material to 30 be continuously agitated as it passes over the screen table whereby it may be thor-

oughly washed if so desired and whereby all of the under sized pieces are caused to fall through the screen openings.

While I have shown and described the 35 preferred embodiments of my invention it will be clearly understood that I do not wish to be limited to this construction, but may make such changes as will fall within the scope and spirit of the invention as claimed. 40

What I claim is:—

A grader comprising a support, a series of fixed parallel spaced bars mounted in an inclined position therein and having their upper edges smooth and lying in the same 45 plane, spaced parallel shafts passing through the bars at points between the upper and lower edges thereof, means positively connecting the shafts together for simultaneous rotation in the same direction, fingers arranged in spiral rows on the shafts and located in the spaces between the bars, said fingers being curved longitudinally and having end portions which move above the 50 upper edges of the bars as they rotate about the axis of the shaft, these fingers being of such length with relation to the distance between the adjacent shaft as to provide substantial sifting spaces when horizontal. 55

In testimony whereof I affix my signature. 60

WILSON PINES.
